[57] CLAIM

The ornamental design for an automatic teller machine,
as shown and described.

DESCRIPTION

FIG. 1 is a front elevational view of an automatic teller
machine showing our new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a top front perspective view thereof.

The bottom of the design is unornamented.
